APPARATUS FOR MAKING CIGARS AND CIGARILLOS IN CONTINUOUS LENGTHS

Wilhelm Walter, Baden, and Friedrich Pietruska, Memmingen, Germany

Application January 23, 1951, Serial No. 207,330

Claims priority, application Germany
January 25, 1950

5. Claims. (Cl. 131—66)

1

This invention relates to an apparatus for the production of cigars and cigarillos. It has already been proposed to produce these products mechanically, and, in particular, to provide an individual casing and wrap each casing about the smoking article mechanically. However, in this operation considerable difficulties have arisen and, moreover, the operation is so slow that no substantial improvement over the known hand methods is attained.

Cigarette machines, which have the greatest operating speed in the production of smoking articles, would appear to be the solution to the problem. However, these machines required (for efficient operation) a tension resisting continuous sheet or covering for the tobacco, such as tension resisting cigarette paper, for example, and, hence, such machines would, ordinarily, be unable to handle the production of cigars, or the like.

Notwithstanding these difficulties, the invention solves the problem of a mechanical production of cigars, cigarets, stumps and the like in continuous lengths. According to the invention a length of tobacco is produced in a type of cigarette making machine from a tobacco filling and a strip-shaped continuous covering composed of tobacco leaves, the said tobacco-leaf strip being supported in its passage through the machine by an auxiliary strip of paper or the like which is loosely associated therewith, the said paper strip functioning to strengthen the tobacco covering strip and thus relieve it of any tension exerted by the shaping belt, the said auxiliary strip then being removed after the formation of the tobacco length.

Thus, according to the invention, the auxiliary belt carries all the tension or strain which, in cigarette making machines is imposed on the cigarette paper, and here would have been imposed on the tobacco covering strip.

The covering strip of tobacco leaves used in the process according to the invention can for example be prepared according to the following process. The residual half leaves remaining after removal of the mid ribs are caused to adhere to one another on a belt so that a continuous strip of any desired length results. The tobacco leaves can be adhered or folded together or can be both caused to adhere and folded. The strip obtained is then divided by cutting into longitudinal strips of suitable width or, if it is narrow, is only trimmed at the edges. The covering strips so obtained have an adequate coherence for handling.

2

So that the covering strip so obtained may not be subjected in any part of the machine to undesirable mechanical strains, it is preferably, during its production, wound together with an auxiliary strip of paper or the like onto a spool. The auxiliary strip and the covering strip are then drawn off this spool together.

An apparatus for carrying out the process according to the invention is illustrated by way of example in the figures forming part of this specification, wherein schematically:

Fig. 1 is a side elevation of an apparatus according to the invention;

Fig. 2 is a cross-section taken on line II—II of Fig. 1;

Fig. 3 is a cross-section taken on line III—III of Fig. 1;

Fig. 4 is a cross-longitudinal section of the shaping parts;

Fig. 5 is a plan view of the shaping parts of Fig. 4;

Fig. 6 is a cross-section taken on line VI—VI of Fig. 4;

Fig. 7 is a cross-section taken on line VII—VII of Fig. 4;

Fig. 8 is a cross-section taken on line VIII—VIII of Fig. 4;

Fig. 9 is a cross-section taken on line IX—IX of Fig. 4;

Fig. 10 is a cross-section taken on line X—X of Fig. 1.

Figures 2 to 10 are shown in enlarged scale.

Referring to the general arrangement shown in Fig. 1, 2 is a table-like frame composed by two basic parts 3 and 5 and the plate 7. On the frame 2 is mounted the feeder 4, the casing of which is partly broken away to show the conveyer 6 from which the tobacco falls on the chute 8.

The chute 8 supplies the tobacco to the U-shaped channel member 10. In the U-shaped channel member 10 is guided a tobacco conveyer belt 12 running round the pulleys 14, 16 and 18 and driven by a driving roller 20. The bearings of the shafts for these pulleys and the driving roller are mounted in the frame 2. The driving roller 20 may be driven by convenient means as an electric motor or the like (not shown).

The tobacco charge lying on the tobacco conveyer belt 12 guided in the channel member 10 is formed by this channel member into a strand or rope 23 and compressed by the pressing wheel 22 and the pressing roller 24 surrounded by the U-shaped pressing plate 25. The tobacco strand is then pushed over the funnel-shaped bridge-member 26 into the inlet-funnel 28.

The arrangement for forming the cigars and cigarillos is also mounted on the frame 2. On a bracket 30 connecting the two-frame parts 3 and 5 is secured by two bearings (not shown) the supply-spool 32. On this spool is wound the tobacco covering strip 34 and the auxiliary strip 36 preferably made of paper. The two strips 34 and 36 run between two guide pulleys 38 and 40 and across an adhesive device 42 mounted on the bracket 30. The covering strip 34 and the auxiliary strip 36 then move together over pulley 44 mounted on a shaft pivotally secured in the plate 7 of the frame 2. The two strips 34 and 36 then move beneath the tobacco charge coming from the bridge 26, and the strips and the tobacco filling then move together into the inlet-funnel 28. On this part of the plate 7 is guided a shaping-belt 46 running over the pulleys 44, 50, and 52 and driven by the driving roller 54, as is shown more in detail in Figs. 4 and 5. The driving roller 54 may be driven by convenient means as an electric motor or the like (not shown). The shaping belt 46 takes up the tobacco charge lying on the two strips 34 and 36 and pulls the strips and the charge through the inlet-funnel 28 to the shaping channel 56. This channel is overlapped by the shaping members 58 and 60 (see Fig. 5) rounded on their inlet-portions 62 and 64. These shaping members 58 and 60 are secured by bolts 63 and 65 or the like to the channel 56. In Fig. 7 there is shown a section taken on line VII—VII of Fig. 4 illustrating the overlapping of the two shaping members.

After leaving the shaping members 58 and 60 the combination of tobacco charge 23, covering strip 34, auxiliary strip 36, and shaping belt 46 moves through the outlet-finger 66 to the seam smoothing iron 68 which may be electrically heated. The outlet finger 66 is shown more in detail in Figs. 4, 5 and 8 and has a bridge part 67 secured by bolts 69 to the shaping channel 56. The smoothing iron 68 is shown more in detail in Fig. 9 and may be provided with a smoothing edge 71 heated by a device 73 in convenient manner, such as by electrically energized windings or the like (not shown). Having passed the smoothing iron 68 the auxiliary strip 36 and the shaping belt 46 are separated from the tobacco charge surrounded by the covering strip 34. The auxiliary strip 36 is then wound on the storage spool 70 positioned on the frame part 5 in any convenient manner. The shaping belt 46 returns over the driving roller 54 and is ready for further use.

The tobacco charge 23 surrounded by the sealed covering strip 34 moves to a cutting device generally marked by the reference number 72 shown more in detail in Fig. 10. The cutting device comprises an eccentric knife 74 pivotally mounted on a shaft 76 secured in bearings conveniently fixed in the casing 78 shown in section in Fig. 10. The shaft is driven by convenient means, such as an electric motor or the like (not shown). The knife 74 moves into a slot 80 in a tube composed of the two portions 82 and 84. The tobacco charge 23 surrounded by the sealed covering strip 34 passing the tube 82, 84 is cut by the knife 74 and the cut portions thereof as cigars and cigarillas are pushed out onto a conveyor 86 arranged at the end of the machine. The cigars or the like may be transported through the conveyor 86 to a packing machine.

The operation of the machine described above is as follows:

The cut tobacco falls from the feeder 4 onto 76 strip in the case of cigarette machines.

the conveyor 6 and is supplied to the chute 8. From the chute the cut tobacco slides onto the conveyer belt 12 guided in the U-shaped channel member 10. In this channel member 10 and between the pressing wheels 22 and 24 and the pressing plate 25 it is formed to a strand or rope which is forwarded by the conveyer belt 12.

On the storage spool 32 the tobacco strip 34 and the auxiliary strip 36 are wound so that the auxiliary strip which may be made of paper, lies beneath the corresponding portion of the tobacco strip 34. The width of the strips is such that the tobacco strip overlays the auxiliary strip on one side about 2 mm. The width of the tobacco strip is a little greater than the circumference of the cigar or like to be made. The guiding of the two strips is such that the pull exerted by the shaping belt 46 is always transmitted to the auxiliary strip 36, i. e. this strip lies on the guiding pulleys 40 and 44 respectively.

Through the pulleys 38, 40 the combination of the two strips 34, 36 moves to the adhesive device 42. The wheel 43 dipping into a container containing an adhesive material applies an adhesive seam to the edge of the tobacco strip 34 supported by the auxiliary strip 36.

The combination of the two strips 34 and 36 meets the tobacco charge coming from pressing device 22, 24, 25 and running through the bridge 26 on the inlet-pulley 44. The tobacco charge combined with the two strips enters the shaping channel 56 the raised sides of which bend the edges of the strips upwardly. The upwardly bent edges of the strips enter the shaping members 58 and 60. These overlapping members bend the strip edges one upon another. The holding together of the tobacco charge is insured by the inlet-funnel 28, as is shown in more detail in Fig. 6. The overlapping of the strip edges is illustrated in Fig. 7 from which it may be seen that one edge of the strips is beneath the member 60 while the other edge is between the members 58 and 60. The strip edges lying between the members 58, 60 are correctly registered and the underlying tobacco strip on its inner side is provided with the adhesive seam. The other strip edges underlying the member 60 are not correctly registered because the auxiliary strip edge is narrow relative to the tobacco strip. In leaving the shaping members 58, 60 the tobacco strip edge provided with adhesive seam therefore lies directly on the other tobacco strip edge. In this condition the tobacco charge surrounded by the two strips enters the seam smoothing iron 68 which effects the sealing of the longitudinal seam. After sealing the tobacco strip 34, the shaping belt 46, and the auxiliary strip 36 pass over the pulley 52. Now the length of the tobacco strand moves to the cutting device 72 and is cut off and finally removed by the conveyor 86 as finished cigars and cigarillas. The cut off cigars, cigarillas, stumps or the like can also be further processed, as for example, they may be provided and shaped with a wrapping. It is also possible to lead the uncut length further and enclose it with a wrapping strip in a like or similarly constructed machine before cutting up.

From Fig. 1 it is to be observed that all positions of change of direction through which the covering strip and auxiliary strip pass together are so disposed that the auxiliary strip traverses the shorter path, that is to say, lies on the inside. This arrangement offers substantial advantages and is distinguished from the path of the paper

While we have described and shown in the foregoing specification and drawings a preferred embodiment of the invention, it will be understood that many changes and alterations may be effected without departing the scope of the following claims. For instance, all moving parts, as conveyer 6, driving roller 20, driving roller 54, cutting knife 74, spool 10, and conveyer 86 may be driven by a common driving device as an electric motor or they may be driven by separate motors suitably synchronized.

What we claim is:

1. Apparatus for producing cigars and cigarrillos comprising a feed belt for longitudinally feeding tobacco filling, an auxiliary strip having thereon a tobacco strip in the form of a roll, means for feeding said strips from said roll under the path of said filling and adjacent to the discharge end of said feed belt to permit said filling to be deposited on said tobacco strip, a shaping member adjacent to said discharge end of said feed belt through which said filling and strips are adapted to pass, a shaping belt having means for advancing said filling and strips through said shaping member and adapted to carry said strips, an ironer beyond said shaping member for sealing said tobacco strip about said filling, and means for separating said auxiliary strip from said sealed tobacco strip and filling.

2. Apparatus for producing cigars and cigarrillos comprising a feed belt for longitudinally feeding tobacco filling, an auxiliary strip having thereon a tobacco strip in the form of a roll, means for feeding said strips from said roll under the path of said filling and adjacent to the discharge end of said feed belt to permit said filling to be deposited on said tobacco strip, a shaping member adjacent to said discharge end of said feed belt through which said filling and strips are adapted to pass, a shaping belt having means for advancing said filling and strips through said shaping member and adapted to carry said strips, and adhesive applicator adjacent to said shaping member for applying adhesive to the edge of said tobacco strip, an ironer beyond said shaping member for sealing said tobacco strip about said filling, and means for separating said auxiliary strip from said sealed tobacco strip and filling.

3. Apparatus for producing cigars and cigarrillos comprising a feed belt for longitudinally feeding tobacco filling, an auxiliary strip having thereon a tobacco strip in the form of a roll, means for feeding said strips from said roll under the path of said filling and adjacent to the discharge end of said feed belt to permit said filling to be deposited on said tobacco strip, a shaping member adjacent to said discharge end of said feed belt through which said filling and strips are adapted to pass, a shaping belt having means for advancing said filling and strips through said shaping member and adapted to carry said strips, the width of said tobacco strip

being greater than that of said auxiliary strip, an ironer beyond said shaping member for sealing said tobacco strip about said filling, and means for separating said auxiliary strip from said sealed tobacco strip and filling.

4. Apparatus for producing cigars and cigarrillos comprising a feed belt for longitudinally feeding tobacco filling, an auxiliary strip having thereon a tobacco strip in the form of a roll, means for feeding said strips from said roll under the path of said filling and adjacent to the discharge end of said feed belt to permit said filling to be deposited on said tobacco strip, a shaping member adjacent to said discharge end of said feed belt through which said filling and strips are adapted to pass, a shaping belt having means for advancing said filling and strips through said shaping member and adapted to carry said strips, said feed belt and shaping belt being in longitudinal alignment, an ironer beyond said shaping member for sealing said tobacco strip about said filling, and means for separating said auxiliary strip from said sealed tobacco strip and filling.

5. Apparatus for producing cigars and cigarrillos comprising a feed belt for longitudinally feeding tobacco filling, a compressing member adapted to bear upon said tobacco filling, an auxiliary strip having thereon a tobacco strip in the form of a roll, means for feeding said strips from said roll under the path of said filling and adjacent to the discharge end of said feed belt to permit said filling to be deposited on said tobacco strip, a shaping member adjacent to said discharge end of said feed belt through which said filling and strips are adapted to pass, a shaping belt having means for advancing said filling and strips through said shaping member and adapted to carry said strips, an ironer beyond said shaping member for sealing said tobacco strip about said filling, and means for separating said auxiliary strip from said sealed tobacco strip and filling.
